UNITED STATES PATENT OFFICE.

DAVID C. BLAKE, OF MARSHFIELD, OREGON.

MOTOR VESSEL.

No. 897,517.

Specification of Letters Patent.

Patented Sept. 1, 1908.

Application filed January 20, 1908. Serial No. 411,629.

To all whom it may concern:

Be it known that I, DAVID C. BLAKE, a natural-born citizen of the United States, residing at Marshfield, in the county of Coos 5 and State of Oregon, have invented certain new and useful Improvements in Motor Vessels, of which the following is a specification, reference being had therein to the accompanying drawing.

10 This invention relates to an improvement in motor vessels, and has for its object, the provision of means for facilitating the propelling of a vessel.

Another object of the invention is the construction of a vessel or boat, or ship, which is provided with a peculiarly-constructed propelling mechanism, whereby a very high rate of speed may be obtained, and said propelling mechanism comprises a minimum 15 number of parts, is efficient in operation, and comparatively inexpensive to construct or manufacture.

A further object of the invention is the construction of a vessel or boat from a plurality of canoe-like sections, the driving means being supported by said canoe-like sections, and part of said means being positioned between each two sections.

With these and other objects in view, the 30 invention consists of certain novel constructions, combinations, and arrangement of parts, as will be hereinafter fully described and claimed.

In the drawings: Figure 1 is a view in side 35 elevation, partly shown in section, of an apparatus or vessel constructed in accordance with the present invention. Fig. 2 is a top plan view of the structure depicted in Fig. 1. Fig. 3 is a transverse, sectional view of the 40 apparatus or motor vessel.

Referring to the drawings by numerals, 1 designates a plurality of canoe-like sections; I, preferably, employ three of these canoe-like sections in the construction of my apparatus or vessel. Each section 1 is provided 45 with a hollow body portion 3, and terminates, at its ends, in upwardly-bowed or curved end-portions 2.

A plurality of boxes 4 are carried by each 50 canoe-like section 1, and each box comprises an upper section 5 and a lower section 6. Journaled in the boxes 4, are transverse, roller or wheel-supporting shafts 7. Fixedly secured to each shaft 7, is, preferably, a pair 55 of hollow or buoyant rollers or wheels 8.

The rollers 8 are provided with angular webs or fins 9 upon their peripheries. The fins or flanges 9, owing to their angular structure, materially assist in driving or propelling the vessel through or "over" water, for the 60 reason that a portion of the vessel is really lifted a considerable distance out of the water when a very high speed is attained, owing to the buoyancy of the structure. From the foregoing, it will be noted that the 65 canoe-like sections, as well as the rollers, are hollow and buoyant. Each roller 8 is, preferably, positioned between two parallel, canoe-like sections 1.

The upper portion of each roller is covered 70 by a semi-cylindrical casing 10; the transverse edges of each casing 10 resting upon transverse eye-beams 11, Fig. 1. The eye-beams 11 are positioned between each two contiguous rollers at each side of the vessel 75 and constitute a support for not only the casings 10, but also assist in supporting the longitudinally-extending eye-beams 11^a. The eye-beams 11^a rest upon the top of the casing 10, and also upon the upper ends of 80 the end-portions 2 of the canoe-like sections 1. Front and end casings or concavo-convex guards 12 are secured at the ends of the canoe-like sections for preventing water from passing over the top of the casings 10, 85 as well as preventing water from injuring or wetting the driving gear. If I desire, I may support, upon the platform or floor 13, carried by the eye-beams 11^a, a cabin, as indicated by dotted lines 14, Fig. 3. 90

At one end of the canoe-like sections 1, and, preferably, carried by the center canoe-like section, is a rudder-post or vertical shaft 15, which is provided, at its upper end, with a pulley or wheel 16, by means of which rotary movement may be imparted to the post or shaft 15 for moving the rudder 16. 95

The driving gear for shafts 7 and rollers or wheels 8 comprises disks 17, fixedly secured to the transverse supporting shafts 7, preferably, between the parallel rollers or wheels 8, see Figs. 2 and 3. Each primary, frictional disk 17 extends, preferably, through an elongated aperture or opening 18, Fig. 3, into the central canoe-like sections, and engaging 100 said primary disks are transversely-positioned, auxiliary disks 19, which auxiliary disks are fixedly secured to parallel, longitudinally-extending drive shafts 20. The drive-shafts 20 are journaled in transverse 105 110

bearings 21 carried by the top of the central canoe-like section, and each bearing is, preferably, formed of sections that are held together by any suitable fastening means 22, whereby the parallel, longitudinally-extending drive shafts 20 can be quickly assembled or disassembled in the construction of the driving mechanism. I, preferably, employ a pair of drive-shafts 20 for increasing the drive-power, as it will be obvious that the two shafts are rotated synchronously, in opposite directions, and thereby a double frictional driving-power is obtained upon the primary disks 17, for rotating the rollers. 15 Any suitable motor power may be utilized for imparting rotary movement to the shafts 20.

It will be obvious that the rollers or wheels 8 constitute propellers or propelling means. 20 What I claim is:

1. In an apparatus of the class described, the combination of a plurality of canoe-like sections, each section comprising a closed body, terminating in upwardly-extending, 25 curved end-portions, a transverse shaft journaled upon said bodies, a roller or propeller fixedly secured to said shaft, a casing covering a portion of said roller, and a beam supported upon the upwardly-curved end-portions and said casing.

2. An apparatus of the class described, comprising a plurality of parallel, canoe-like sections, each section provided with upwardly-curved end portions, inwardly-curved 35 or bowed guards engaging the upwardly-curved end-portions of the sections, and extending downward, and propelling means carried by the canoe-like sections between the guards.

3. In an apparatus of the class described, the combination of a plurality of parallel canoe-like sections, provided with an upwardly-curved, hollow end portion, transverse supporting means positioned contiguous to the ends of and connecting said canoe-like sections, inwardly-bulged guards connected near their upper end to the upwardly-curved end portions and supported at their lower ends upon said supporting and connecting means, and means supported entirely 45 upon said canoe-like sections and positioned between said guards for propelling the canoe-like sections.

4. An apparatus of the class described, 55 comprising a series of parallel canoe-like sections provided with upwardly-extending portions at their ends, rollers journaled between each two sections and arranged in transverse alinement, casings supported by said sections 60 and partly covering the rollers, guard means positioned at the ends of said canoe-like sections and engaging at their upper ends the upper ends of said sections and being adapted to prevent liquid from passing over the top of 65 said casings, and means positioned between

the rollers and the casings and being capable of imparting rotary movement to the shafts and rollers.

5. An apparatus of the class described, comprising a plurality of buoyant sections, a transverse shaft supported upon said sections, a roller or propeller fixedly secured to said shaft between said sections, a semi-cylindrical casing carried by said sections and covering the upper portion of said propeller, and a beam supported upon and engaging the upper portion of said casing. 75

6. An apparatus of the class described, comprising a series of buoyant sections, shafts journaled upon said sections, rollers 80 arranged parallel and in alinement and fixedly secured to the shafts between the sections, a plurality of semi-cylindrical casings covering the upper portions of said rollers and supported upon said sections, and a plurality of longitudinally-extending eye-beams supported upon the upper portion of the casings. 85

7. An apparatus of the class described, comprising a series of parallel canoe-like sections, each section provided with upwardly-curved, hollow end portions, propelling means supported upon and positioned between each two sections, casings covering said propelling means and supported upon 90 said sections, and longitudinally-extending beams supported upon the upper portion of said casings and the upper ends of said end-portions. 95

8. An apparatus of the class described, 100 comprising a plurality of hollow, buoyant sections, transverse eye-beams positioned upon and connecting said sections, longitudinally-extending eye-beams positioned above said transverse eye-beams and supported upon said sections, and propelling means supported upon said sections between 105 each two contiguous eye-beams.

9. An apparatus of the class described, 110 comprising sections, each section provided with a body and with upwardly-extending ends, transverse eye-beams supported upon the body, longitudinally-extending eye-beams supported upon the upwardly-extending ends and above the transverse eye-beams, a casing 115 supported upon each two contiguous transverse eye-beams, and propelling means carried by each two contiguous sections and positioned within each casing.

10. An apparatus of the class described, 120 the combination with buoyant supports, of a shaft journaled upon said supports, a roller or propeller fixedly secured to said shaft, a primary disk fixedly secured to said shaft, parallel drive-shafts positioned contiguous to 125 said disks, and auxiliary disks fixedly secured to said drive-shafts and engaging the opposite sides of said primary disk.

11. In an apparatus of the class described, 130 the combination of canoe-like sections, jour-

nal-boxes formed upon said sections, a shaft journaled in said boxes, a roller or propeller fixedly secured to said shaft between said sections, a primary frictional disk fixedly secured to said shaft, and said disk extending into one of said canoe-like sections, transverse, parallel bearings carried by the upper portion of the canoe-like section into which the primary disk extends, parallel drive-shafts journaled in said transverse bearings, and positioned upon opposite sides of said primary disk, auxiliary, frictional disks secured to said drive shafts between said transverse bearings and upon opposite sides of and engaging the primary frictional disk.

12. In an apparatus of the class described, the combination of a plurality of canoe-like sections, a supporting shaft journaled upon the upper portion of said canoe-like sections, a frictional disk fixedly secured to said supporting-shaft and extending down into one of the canoe-like sections, a roller or propeller fixedly secured to said supporting-shaft between two contiguous canoe-like sections, and means engaging the side of said frictional disk for imparting rotary movement thereto and thereby driving the roller or propeller.

13. In a mechanism of the class described, the combination with a support, of a supporting-shaft carried by said support, propelling means fixedly secured to said shaft, a rotatable member fixedly secured to said supporting-shaft to one side of said propelling means, and means engaging the opposite portions of said rotatable bearing and being capable of imparting rotary movement thereto for rotating said propelling means.

14. In an apparatus of the class described, the combination of a series of parallel canoe-like sections, a transverse, supporting shaft journaled upon all of said sections, a pair of rollers fixedly secured to said shaft, each roller positioned between each two contiguous canoe-like sections, a frictional, primary disk secured to said shaft between the rollers

and partly positioned above and below the upper face or surface of one of the canoe-like sections, transverse, sectional bearings carried by the canoe-like section and partly surrounding the frictional disk, longitudinally-extending, parallel shafts positioned above the canoe-like section carrying the sectional bearings, said parallel shafts journaled in said sectional bearings, and auxiliary frictional disks fixedly secured to the shafts between two transverse bearings and engaging opposite sides of the primary frictional disk.

15. In an apparatus of the class described, the combination of a canoe-like section, a shaft journaled upon said section, propelling means fixedly secured to said shaft, means for rotating said shaft and propelling means, said canoe-like section provided with an upwardly-extending end, an outwardly-bulged guard engaging the upwardly-extending end of said section, a rotatable post extending through the canoe-like section and through said guard, a wheel or actuating member positioned above said guard and fixedly secured to the shaft near its upper end, and a rudder fixedly secured to said shaft below the canoe-like section.

16. In an apparatus of the class described, the combination of a canoe-like section terminating at its ends in upwardly-extending end portions, said end-portions positioned above the central portion of said section, horizontal supporting means in engagement with only the upper portion of and connecting the upwardly-extending end portions, and propelling means supported upon the canoe-like section and positioned below the supporting means.

In testimony whereof I hereunto affix my signature in presence of two witnesses.

DAVID C. BLAKE.
